OIL BURNER FOR TOBACCO CURING BARNS

Ralph W. Duffell, Henderson, N. C.

Application August 17, 1951, Serial No. 242,377

1 Claim. (Cl. 158—57)

The present invention relates to certain new and useful improvements in an oil burner which is expressly adapted for practical and efficient use in a tobacco drying and curing barn and it has more particular reference to a burner whose components are properly and specially assembled for use in association with conventional distributing flue means and a stack which is connected with said flue means.

Tobacco curing burners which are known and in use are generally employed in pairs and it is an object of the instant invention to provide a burner whose unusual and unique construction increases the efficiency of operation to the point that ample heating and drying results may be obtained through the medium of a single burner and flue arrangement.

Another object of the invention is to provide an oil burning tobacco curing or curing burner which is possessed of highly desirable features of refinement and distinction, these being harmoniously organized to provide an over-all burner construction in which manufacturers and users will find their respective requirements fully met and which is in keeping with the rigid safety requirements of State laws in which burners in this field are most likely to be used.

Another object of the invention is to provide a tobacco curing burner which is simple, economical, practical, efficient for original installation and repair requirements and utilizes a novel oil receiving, vaporizing and burning ring and a complementary underlying base unit, said unit being characterized by a trough which is properly associated with the ring for preliminary priming, preheating and starting purposes.

More specifically, novelty is predicated upon a structurally distinct casting which forms the stated base unit, the latter having a trough with an outstanding apertured plate encompassing its outer perimeter and providing a ledge for seating a flue adapter cone, the inner peripheral portion of the trough having flange means which in turn is provided with an excess oil over-flow and retrieving channel.

Further novelty is predicated on a base unit having the stated trough and other features and a perforated oil burning and vaporizing ring above the open top of the trough, said ring having an adjustable depending pipe which delivers oil from the ring into the trough in a satisfactory manner.

What is more, novelty has to do with the trough, burner ring combination in conjunction with a water container which is included in the immediate vicinity of the burner ring and which in this position, serves to heat and vaporize the water, allowing the water vapor jets to mingle with the gas jets and to in this manner provide a highly efficient and economical fuel combustion and burning result.

Other objects and advantages will become more readily apparent from the following description and the accompanying sheets of illustrative drawings.

In the accompanying drawings:

2

Figure 1 is a top plan view of the burner constructed in accordance with the principles of this invention with parts broken away and shown in section and with the flue and flue adapter means omitted for clearness of illustration of the parts;

Figure 2 is a view partly in section and partly in elevation which is taken on the irregular line 2—2 of Figure 1, looking in the direction of the arrows;

Figure 3 is a horizontal section on the line 3—3 of Figure 2, looking in the direction of the arrows;

Figure 4 is a view of a diagrammatic nature which shows a typical plan of a tobacco curing barn, the single tobacco curing burner, flue assembly and other components;

Figure 5 is also a view in section and elevation which shows somewhat diagrammatically the manner in which water is delivered to the water supply means in the burner from a remote lever controlled source; and

Figure 6 is a view similar to Figure 2 showing a modification in construction, said view being fragmentarily presented and contracted somewhat in dimensions.

Referring now to the drawings and first to the form of the invention characterized in Figures 1 to 5 inclusive reference is had first to Figures 1 to 3. Here the aforementioned base unit is denoted by the numeral 8 and, as mentioned, this takes the form of a single casting provided with suitable supporting legs 10 adapted to rest on the ground in the tobacco barn. An essential part of the casting is the aforementioned open top oil receiving, priming and preheating trough 12. This is of annular form and attached to the bottom of the outer peripheral wall thereof is a circular horizontal plate 14 whose top is provided at the outer perimeter with an upstanding rib 16. This plate is also provided with elongated or suitable air passing slots 18 and also serves as a ledge to support the truncated conical flue adapter 20. The lower end of the adapter rests on the ledge-plate and is held in place by the shoulder provided by the rib 16. There is a suitable baffle plate 22 on the interior of the adapter. The inner wall 24 is provided with a circular flange portion 26 providing an air passage at 28 and also constructed to provide a shallow oil overflow and retrieving channel 30. The return pipe 32 is connected with this channel and is in turn connected to a horizontal pipe 34 which extends underground and drains the line from the burner into a suitable oil retrieving sump. Incidentally, the pipe 34 just mentioned, shown in dotted lines in the diagram in Figure 4, and the sump is denoted by the numeral 36.

The aforementioned oil receiving and vaporizing burner ring is denoted by the numeral 38. This is of tubular as well as annular form and is of a diameter so that it is disposed in spaced parallelism above the open top of the trough 12. It is provided with ports 40 in the manner best shown in Figure 2. It is supported by a vertical standing pipe or the like 42 which has a lateral branch 44 communicating with the oil space in the ring 38. If preferred the ring may be provided with depending legs 46 and these, in practice, will rest in the trough 12 to assist in maintaining the parts in concentric relationship. In addition the oil ring 38 is provided with one or more communicating pipes between itself and the trough. One such pipe is denoted at 48 in Figure 2 and has its threaded upper end 50 adjustably connected with the underside of the ring and extending half way up into the oil space in the ring. The oil level is thus maintained at the point denoted by the numeral 52. The lower end of the pipe extends down into the space of the trough and terminates short of the bottom of the trough.

The numeral 54 denotes a suitably shaped and pro-

portioned water containing tank or equivalent container. This has a circular top portion 56 whose marginal edge portion 58 rests on and coacts with an inner water vaporizing ring 60. This ring surrounds the tank and is joined thereto by connections 62 and is provided with orifices or ports 64 opposite to the ports 40 and cooperating with the latter in an obvious manner. The water ring is also provided with short legs or feet 66 and these rest on the ledge flange 26 as shown in Figure 2. The water pipe which delivers water to the heating and vaporizing tank is denoted by the numeral 68 and this is joined by a vertical pipe 70 directly to the tank. As best shown in Figure 5 this water pipe is communicatively connected to a well or other suitable reservoir 72 which constitutes a source of supply. Float controlled valve means 74 is provided so that the water level in the tank 54 corresponds to the level of the water in the supply reservoir 72 thus preventing too much water from entering the water ring 60.

Reverting for a moment to Figure 2 and to the pipe means 42 this receives oil by way of the pipe 76 which has an over-flow and venting pipe 78. Pipe 76 as shown in the diagrammatic view in Figure 4 is connected with a safety oil feed regulating valve 80 which communicates by way of a cut-off valve 82 with the supply tank 84. Incidentally in Figure 4, the numeral 86 designates a spring which is connected with cable means 88 which in turn is joined by a fusible safety link 90. This arrangement is for automatically cutting out the supply of oil to the burner if heating conditions within the barn become abnormal.

Also as shown in Figure 4, there is a single burner provided and this connected with the flue means by way of a union 92 and the associated flue branches 94, 96 and 98. These branches join up with an externally disposed stack 100. Reverting to the so-called union 92, this is provided with a depending inlet duct 92a which telescopes over the truncated upper end of the conical adapter 20. Thus, when the burner is in operation the heated air is transmitted by way of the adapter 20 into the union 92 and then distributed through the circulating branches of the flue means in the barn.

In operation, it is necessary to make sure that the safety cut-off valve 82 is, of course, open and that the valve closing cable means 88 is properly connected by way of a fusible link 90. The oil control valve is opened and oil is allowed to flow by way of the pipe means 76, 42 and 44 into the oil vaporizing and burner tube or ring 38. When the oil fills to the level shown at 52 in Figure 2 it then overflows the upper threaded end of the trough filler pipe 48 and gravitates through the pipe into the trough and produces a well of oil in the trough 12. It is then necessary to turn the control valve back to low fire stage and to ignite the priming oil in the trough. This can be done by way of a torch (not shown) or absorbing wadding material or waste which is saturated with oil and set on fire. The flaming oil in the trough preheats the oil in the burner ring 38 and continues to do so until the stage arrives, after about 10 or 15 minutes, to turn the control valve to a higher heating stage. To raise the heat the oil control valve is opened gradually allowing several hours more or less to reach the desired stage and the incoming oil into the ring 38 is vaporized and the gas escapes in the form of jets by way of the orifices 40. Also by radiation and direct flame the water in the tank or container 54 is heated and gradually turned into vapor and escapes under pressure through the ports 64. Thus, by providing a pair of concentric coplanar ported cooperating rings and commingling the water vapor and vaporous gas mix a highly combustible good flame producing fuel and consequent fire is unquestionably had.

Attention is called to the novel base means or casting unit 8 which is characterized by the oil receiving and priming trough wherein the annular plate or flange 14

projects in the plane from the bottom, provides passages for air and also provides a satisfactory ledge or seat for the lower end of the readily applicable and removable adapter cone, and wherein the inner wall of said trough has an elevated flange which provides the overflow channel and also a satisfactory seating and supporting ledge for the water ring 60, the feet 66 thereon and the interconnected tank 54 which is concentrically located in the opening means 28.

10 A simpler construction is shown in the modification seen in Figure 6 wherein the trough in the base unit 102 is denoted by the numeral 104. The trough here has an outstanding plate, a ledge forming flange 106 with a marginal rib 108 supporting the lower end of the conical adapter 110. The air slots are denoted at 112. The overflow and return channel is denoted at 114 and the supporting legs at 116. The return pipe 118 connects with the overflow channel. The oil delivery pipe 120 feeds oil by way of the elbow 122 into the oil heating and vaporizing ring or tube 124. This has orifices 126 and there is a filler pipe 128 which connects with the oil space in the ring and depends into the oil space of the trough. The ring has supporting legs 128 resting in the trough. In this form of the invention the inner water heating and vaporizing ring is dispensed with and the container or tank 130 takes its place. Here the tank is a simple container which is positioned above the over-flow channel and is suitably supported and has its wall provided with ports 132 which cooperate with the ports 126 in providing the desired interposed water and fuel mixing space between the periphery or wall of the tank and the inner periphery of the burner ring 124. The water delivery pipe, which keeps the water in the tank at a constant level, is denoted by the numeral 134.

20 35 It is thought that persons skilled in the art to which the invention relates will be able to obtain a clear understanding of the invention after considering the description in connection with the drawings. Therefore, a more lengthy description is regarded as unnecessary.

40 40 Minor changes in the shape, size and arrangement of details coming within the field of invention claimed may be resorted to in actual practice, if desired.

Having described my invention, what is claimed as new is:

45 45 An oil burner for use in tobacco curing barns comprising a horizontally disposed tubular burner ring provided around its inner peripheral portion with gas emitting ports, conduit means communicatively connected with said ring and serving to feed oil from a valve controlled source to said ring, an elevated base unit having a horizontal open top endless trough located in spaced relation directly beneath said burner ring, a vertical pipe adjustably connected with and having its upper end extending into the oil space in said ring and also having its lower end depending into said trough to a point adjacent the bottom of the trough, said base unit embodying an annular plate projecting outwardly beyond the outer peripheral portion of said trough and provided with air passages and further provided with outer marginal shoulder means and constituting an annular ledge, a truncated adapter cone having its base portion resting on said ledge and held against displacement by said shoulder means, the inner peripheral portion of said trough having an endless oil overflow and retrieving channel, a water receiving and containing tank mounted in concentric relation in respect to the inner peripheral portion of said burner ring, said tank having a vertical wall provided with orifice means, and a water ring interposed between and encircling the vertical wall of of said tank and spaced radially from the inner peripheral portion of said burner ring, the inner peripheral portion of said water ring being in close proximity to and communicatively connected with the orifice means in said vertical wall and having its

outer peripheral portion provided with orifices cooperating operatively with the orifices in said burner ring.
